US00D763265S

(12) **United States Design Patent**
Trujillo(10) **Patent No.:** **US D763,265 S**
(45) **Date of Patent:** **** Aug. 9, 2016**

- (54) **DISPLAY SCREEN WITH ICON FOR DISPLAYING A LUBRICATION MANAGEMENT SYSTEM**
- (71) Applicant: **Gerardo Trujillo**, Leon (MX)
- (72) Inventor: **Gerardo Trujillo**, Leon (MX)
- (**) Term: **14 Years**
- (21) Appl. No.: **29/456,954**
- (22) Filed: **Jun. 5, 2013**
- (51) LOC (10) Cl. **14-04**
- (52) U.S. Cl.
USPC **D14/485**
CPC **G06F 3/04817** (2013.01)
- (58) **Field of Classification Search**
USPC D14/485-495; 715/700-867, 973-977
CPC G06F 3/0481-3/0486
See application file for complete search history.
